UNITED STATES PATENT OFFICE.

FREDERICK W. C. NEUNER, OF CONNERSVILLE, INDIANA, ASSIGNOR TO INDIANA LAMP CORPORATION, OF CONNERSVILLE, INDIANA, A CORPORATION.

REFLECTOR-SUPPORTED LIGHT-SOCKET MOUNTING.

Application filed April 22, 1927. Serial No. 185,803.

This invention relates to the mounting of a light bulb supporting socketed plug upon a reflector.

The chief object of the invention is to detachably but rigidly mount a light bulb supporting socketed plug upon a reflector such that the filament is positioned in predetermined relation to the reflector focus or reflecting surface.

10 The chief feature of the invention consists in the provision of a reflector supported plug receiving sleeve and yieldingly associating therewith a light bulb supported socketed plug, said sleeve and plug having a detachable and pin and slot connection for rigidly but detachably connecting the same for predetermined positioning.

20 The full nature of the invention will be understood from the accompanying drawings and the following description and claims:

Fig. 1 is an elevational view of one form of the invention. Fig. 2 is a longitudinal sectional view taken on line 2-2 of Fig. 25 1 and in the direction of the arrows. Fig.

3 is a longitudinal central sectional view of a modified form of the invention. Fig. 4 is an elevational view of the reflector supported socket support shown in Fig. 3. Fig. 30 5 is an elevational view of the light bulb supporting socketed plug shown in Fig. 3.

In the drawings 10 indicates a reflector rigidly mounting in its central aperture 11 a sleeve 12. Said sleeve includes a pair of 35 bayonet or J-slots 13 in opposed or diametrical relation. The sleeve is open at both ends and slidably and rotatably receives a light bulb supporting socketed plug 14 which includes the J-slots 15 at its forward end

40 to receive a light bulb 16 having the co-operating anchoring pins 17 and including a filament 18 which is adapted to coincide with the focus of the reflector or to be positioned in predetermined relation with reference to 45 the reflecting surface.

The plug supports a pair of radially extending pins 19 and herein the same are

shown separated and oppositely extending, said pins being receivable by the sleeve slots 13 for anchoring the plug 14 in the sleeve 50 and in predetermined relation to the reflector 10. Bearing against pins 19 is a washer or retaining ring 20 and interposed between said ring and the anchoring flange 21 of the sleeve is a coil spring 22 for normally maintaining pins 19 seated in the offset portion 23 of the J or bayonet slot 13 for yieldingly retaining the plug in predetermined position in the sleeve.

In Fig. 3 a modified form of the invention 60 is illustrated, and herein the reflector 10 supports a sleeve 112 in turn supporting a spring 22 and a washer or ring 20, said sleeve 112 having the J-slot 113 with the anchoring offset seat portion 123 therein to 65 receive tongues 119 struck from the plug 114 at 109. Said plug 114 includes a bayonet slot 115 for receiving the pins 17 of the light bulb 16. In this form of the invention the slot receivable pins are formed integral 70 with and from the plug exterior shell portion.

The invention claimed is:

1. In a head lamp construction, the combination of a reflector supported sleeve, a 75 plug slidably and rotatably receivable thereby, said plug including in one end a light bulb receiving socket, a plurality of anchoring slots in said sleeve, a plurality of co-operating pins seatable in said slots for detachably connecting the plug and sleeve, a retainer slidably mounted on said sleeve and retained thereon by said pins, and yielding means for maintaining the pin and slot connection intact, said retainer being interposed 85 between said pins and yielding means.

2. A device as defined by claim 1 characterized by said pins comprising outwardly directed projecting portions formed integral with the plug.

In witness whereof, I have hereunto affixed my signature.

FREDERICK W. C. NEUNER.
